UNITED STATES PATENT OFFICE

JOHN W. DENNIS, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA

FORM FOR SHAPING AND DRYING HOSIERY AND THE LIKE

Application filed January 21, 1929. Serial No. 334,086.

This invention relates to forms useful in shaping and drying knitted articles such as hosiery, and more particularly to shaping and drying forms heated from within as by 5 electricity.

In the main, my invention is directed toward enabling adaptation of forms of the character referred to so that articles of different sizes can be shaped by them, and 10 toward attaining this desideratum without impairment in the heating efficiency of the forms, through provision of simple, inexpensive and easily adjusted means for the purpose.

15 Other objects and attendant advantages will appear from the detailed description which follows when taken in connection with the drawing whereof Fig. I is a side elevation of a hosiery shaping and drying form conveniently embodying my invention.

20 Fig. II is a fragmentary detail view, on a larger scale, with parts broken away to show the interior construction of the form at the heel region; and,

25 Fig. III is a cross sectional view, taken as indicated by the arrows III—III in Fig. II.

For convenience of delineation herein I have shown my invention as embodied in a 30 hosiery shaping and drying form, whereof the body is designated by the numeral 10, the same having the thin flat profile configuration which is to be imparted to the stockings. In the present instance, the form 10 is constructed with side wall members 11 of sheet metal which are separated by a perimetric edge strip 12—likewise of sheet metal—with provision of a coextensive hollow at the interior. The several parts of 35 the structure are secured together at intervals by screws or rivets 13 with the perimetric strip 12 projecting marginally as at 14 to provide a comparatively sharp creasing edge substantially all around the form.

40 Within the hollow of the form body 10 is placed an electric heating element formed by winding a resistance wire or tape 15 about a thin flat insulating core piece 16, of asbestos or the like, having the same general configuration as the form itself, together with 45 outer sheets 17 of insulatory material to pre-

vent short circuiting of the winding, all more or less after common practice in this art.

In suiting the construction of a form such as just briefly described to the purposes of my invention I make in the perimetric strip 12, for example at the heel region, a recession 20, with formation between the rounded heel cheeks 21 of the side wall members 11, of an isolated edge slot 22. Within this edge slot 22 I place, with capacity for movement from the substantially retracted normal position, shown in dotted lines in Fig. II, to projected full line position, a supplemental heel piece 23 fashioned to sectoral shape with an eccentric-curvature from sheet metal corresponding in gage substantially to that used for the perimetric strip 12. Attachment of the supplemental heel piece 23 is by means of a screw 25 having its head occupying a surface recess in one of the heel cheeks 21, 50 and its threaded end engaging a nut 26 with a head similarly recessed in the other heel cheek 21 of the form, see Fig. III. From Fig. II it will be noted that the screw 25 is so located as to determine swinging of the heel piece 23 to the positions already indicated, the movement being limited in either direction through contact of the radial edges and the adjoining arcuate portions of said heel piece with the bottom and opposite end 55 walls of the slot 22, respectively.

When small stockings are to be shaped and dried, the supplemental heel piece 23 is obviously placed in the normal dotted line position of Fig. II, out of the way within the 60 confines of the form body. For stockings of larger size the supplemental heel piece 23 is swung or rocked on its pivot 25 to the full line position, thereby adding to the length of the foot as required. By virtue of direct contact of the supplemental heel piece 23 with the cheeks 21 of the side plates 11, the same is effectively heated through conduction from within the form 10. It is also important to note in this connection that drying of the portion of the stocking stretched across the unoccupied part of the slot 22 (with the supplemental heel piece in either retracted or projected position) is insured through action 65 of heat radiating outward through said slot. 70

Having thus described my invention, I claim:

1. A form for shaping hosiery comprising a profile body; and a sectoral piece eccentrically-pivoted within an edge slot in the heel region of said body with capacity for movement from a normal substantially enclosed position within said edge slot to partially projected position to lengthen the foot and thereby adapt the form for stockings of different foot lengths.
2. A form for shaping and drying articles such as hosiery comprising an internally heated hollow profile body with side wall plates separated by a perimetric spacing strip; and a sectoral-heel piece substantially-enclosed normally in an isolated edge slot of the body formed between said side wall plates by a recession in the perimetric strip, said heel piece having capacity for limited pivotal movement outwards to adapt the form for articles of different foot lengths.
3. A form for shaping and drying articles such as hosiery comprising a hollow internally heated body with side wall plates separated by a perimetric spacing strip; and a sectoral-heel piece pivotally engaged in and substantially-enclosed normally by an isolated edge slot of the body formed between the side wall plates by a recession in the perimetric strip, said heel piece being swingable from such normal position to partially projected relation with respect to said slot in adapting the form for articles of different foot lengths.
4. A form for shaping and drying articles such as hosiery comprising a hollow profile body with side wall plates separated by a perimetric spacing strip; a pivoted sectoral-heel piece engaged in and substantially-enclosed normally by an isolated edge slot of the body afforded between the side wall plates by a recession in the perimetric strip, said heel piece having capacity for limited pivotal movement outwards to adapt the form for articles of different sizes; and an electric heating element occupying the hollow of the body aforesaid.
5. A form for shaping and drying hosiery comprising a hollow internally heated profile body with side wall plates separated by a perimetric spacing strip; and a sectoral piece engaged in and substantially-enclosed normally by an isolated edge slot in the heel region of the body afforded between the side wall plates by a recession in the perimetric strip, said sectoral piece having capacity for limited pivotal movement outwards to adapt the form for stockings of a different foot length.

In testimony whereof, I have hereunto signed my name at Philadelphia, Pennsylvania, this 14th day of January, 1929.

JOHN W. DENNIS.
